FIRE ESCAPE

James H. Briggs, Poughkeepsie, N. Y.

Application July 19, 1937, Serial No. 154,449

1 Claim. (Cl. 227—30)

This invention relates primarily to a fire escape of the rope type which is attached to a window casing for the lowering of persons from a burning building and relates more particularly to a device of this kind whereby the speed of descent may be controlled and stops made at intermediate points between the window at which it is attached and the ground, and the body holding means may after each descent be returned to the window from the ground.

While I am aware that devices for this purpose have been devised which employ a body belt and rope attached to the window casing, they employ a hand operated brake for the rope which is attached to the body belt and adapted to slide down the rope therewith, thus creating great friction and which can not be returned to the starting point from the ground but which must be pulled up from above and the brake returned to its original position adjacent to the upper end of the rope before the next person can descend.

The object of the invention is to provide a rope type fire escape or means of descent from a building for one or more persons, and by which stops may be made at intervening points between the starting place and the ground to take on other persons.

Another object of the invention is to provide a device of this kind in which after a person has reached the ground the belt can readily and quickly be returned to the starting point from the ground and in proper position or adjustment for the next person to descend thereby.

Another object of the invention is to provide in a device of this kind means whereby the rate of speed of travel of the person downward can be regulated by such person.

Another object of the invention is to provide a device that may be mounted within a room or outside of a window and which shall be simple of operation, contain few parts and be positive in its action.

In the drawing:

Figure 1 shows the device attached to the inner side of a window casing with the swinging arm extending outward through the open window.

Figure 2 shows a longitudinal sectional view of the device illustrating the detailed construction and combination of parts.

Figure 3 is an end view of the same.

Figure 4 is an enlarged detail sectional view of the friction brake-block.

Referring to the drawing:

The invention as herewith shown and described

comprises a supporting bracket 10 which is attached to the inside of the window casing 42 by suitable means such as bolts passing through the holes 11 formed in said bracket 10 and said bracket is formed with a boss 12 having a vertical bore 13 to which is swingably mounted by the pin 15 the rear member 14 of the swinging arm; the pin 15 is retained in place by the transverse pins 43.

This rear arm member 14 is provided with the aligned bearings 20 for the pin 15 and also a threaded upper hole 17 for the threaded rear end of the upper brace rod 22 and a lower hole 18 for the inner end of the lower brace rod 23 which is held therein by the pin 19.

The outer end of this swinging arm is composed of a member 24 formed with an upper threaded hole 26 for the outer threaded end of the upper brace rod 22 which is secured therein by the jam nuts 27, and a lower hole 43 for the outer end of the lower brace rod 23 which is retained therein by the pin 28.

The lower portion of this arm member 24 is cut away as at 45 for the rope brake-block 31 which is formed with the tapped holes 32 for the attaching screws 30 by which it is secured to the member 24 through the holes 29; the outer end of this block 31 is provided with the tapped holes 33 for the screws 34 by which it is secured to the lower end portion of a flat brace 36.

The upper end of which is secured to the member 24 by the screws 44 threaded therein.

The rope brake-block 31 is preferably of metal but may be of any suitable material and is provided with an angular or tortuous passage 35 extending from the top to the bottom thereof and of a diameter suitable to effect a sliding fit for the rope 37 which is threaded therethrough.

To the end of that portion of the rope 37 that extends downward from the bottom of the block 31 is secured a snap catch 38 to which are detachably secured the rings 40 of the body belt 41; while that portion of the rope 37 that extends from the upper face of the block 31 is intended to be dropped over the side of the block 31 to the ground.

While the angles of the tortuous passage 35 may vary for different weights to be placed on the rope, it has been found that 50 degrees is the most satisfactory.

In the operation of the device, the person desiring to descend from the window passes the body-belt around the body under the arms and secures the ends by the rings 40 to the snap 38 of the portion of the rope 37 extending from the bottom of the block 31, and then drops the upper

portion of the rope 37 that extends from the top of the block 31 to the ground.

He then lets himself out of the window by grasping hold of the upper portion of the rope 37 thus being able to regulate the rate of speed of the rope passing through the passage in the block 31, and also being able to stop the descent at any point such as other windows to take on other persons, which can be done by a very slight pull upon the rope due to the angle at which the passage through the block is formed.

When the passenger has reached the ground he can return the body belt back to the window by pulling on the upper portion of the rope which when no load is on the lower portion will easily slide through the passage in the block, and in

this manner the body belt may be quickly returned for repeated use.

Having thus described my invention, what I claim as new and desire to secure by Letters Patent is:

In a fire-escape of the class described, a rectangular brake-block hingedly connected with a support therefor, and formed with a vertically disposed tortuous rope-passage therein, a rope threaded through said rope-passage with its free end extending directly downward from the lower face of said block, the remaining portion of said rope projecting from the upper face of said block and extending downward over the side of the block.

JAMES H. BRIGGS. 15
